[57] CLAIM

The ornamental design for a furniture protector, as shown and described.

DESCRIPTION

FIG. 1 is a front and top perspective view, in reduced scale, of my new design for a furniture protector, the portion of the figure shown in broken lines representing

an article of furniture and forming no part of the claimed design;

FIG. 2 is a bottom plan view thereof;

FIG. 3 is a top plan view thereof;

FIG. 4 is a left side and top perspective view thereof;

FIG. 5 is a rear elevational view thereof;

FIG. 6 is a front elevational view thereof;

FIG. 7 is a left side elevational view thereof;

FIG. 8 is a right side elevational view thereof;

FIG. 9 is a right side elevational view of a second embodiment thereof;

FIG. 10 is a left side elevational view of the second embodiment thereof;

FIG. 11 is a bottom plan view of the second embodiment thereof;

FIG. 12 is a top plan view of the second embodiment thereof;

FIG. 13 is a left side and top perspective view of the second embodiment thereof;

FIG. 14 is a front elevational view of the second embodiment thereof;

FIG. 15 is a rear elevational view of the second embodiment thereof;

FIG. 16 is a bottom plan view of a third embodiment thereof;

FIG. 17 is a top plan view of the third embodiment thereof;

FIG. 18 is a left side elevational view of the third embodiment thereof, the right side being a mirror image;

FIG. 19 is a left side and top perspective view of the third embodiment thereof;

FIG. 20 is a front elevational view of the third embodiment thereof; and,

FIG. 21 is a rear elevational view of the third embodiment thereof.
